SYRINGE WITH STERILIZATION MEANS**Otto Schüller, Vienna, Austria, and Fred Malek-Naegeli, Berlingen, Switzerland**

Application January 21, 1954, Serial No. 405,469

Claims priority, application Austria January 23, 1953

5 Claims. (Cl. 128—218)

Sterilization of syringes used up to the present only is possible in their disassembled state through boiling or heating. At the moment of applying the syringe, however, such procedure does not afford an absolute surety for sterility, since when assembling the syringe, the piston and cylinder thereof may come in contact with air and perhaps with dust particles, and since through such manipulation germs and spores may enter the syringe.

The main object of our present invention is to provide a syringe which in the sterile state may be kept ready for application with greater security than thus far.

The syringe disclosed by our present invention is distinguished by the fact that its piston comprises a hollow space for receiving a germicidal source of energy, such as a source of heat or ultraviolet radiation, or contains such source, and is made of a material which is resistant against the energy emitted from the source and permeable for such energy; the whole in such combination that the syringe in the assembled state is disinfectable from the inside. It is, of course, possible to disinfect the syringe additionally and, if desired, at the same time also from the outside.

The piston may be a hollow body open at its rear end, in which is insertable the germicidal source of energy for the purpose of sterilizing the syringe. It is also possible, however, to rigidly incorporate a germicidal source of energy in the piston.

The material of the syringe piston advantageously is chosen heat-resistant or, respectively, pervious for ultraviolet rays. The piston may be made, for example, of quartz, ceramic material, Invar steel or of quartz glass or other refractory glass such as Pyrex, Tempax or Jena Instrument Glass.

Syringes having a cylinder made of quartz are known, which are destined for the irradiation of blood from the outside with the aid of a source of ultraviolet radiation. In the syringe disclosed in the present invention, however, irradiation may take place from the inside, which permits an immediate and better utilization of radiation, whereas when irradiating from the outside, only a fraction of the energy emitted from the source of radiation is utilizable, the major portion of such energy being lost through total reflection.

Several examples of the subject matter of the present invention are shown in the accompanying drawing, in which:

Fig. 1 shows a longitudinal section through a first form of the syringe and through a device incorporating a germicidal source of energy inserted in the hollow space of the syringe piston.

Fig. 2 is a longitudinal section through a syringe piston of different construction in which a source of heat is directly and rigidly built into the piston.

Fig. 3 shows the analogous illustration of a syringe piston having a rigidly built-in source of ultraviolet radiation.

2

Fig. 4 depicts a further example of a syringe piston alone in longitudinal section, and

Fig. 5 is a longitudinal section through a last form of the syringe.

5 In Fig. 1, 10 denotes the cylinder and 11 the piston of a syringe. The cylinder comprises a union member 12 for securing an injection needle to the cylinder. Piston 11 is formed as hollow body which is open at one end, i. e. at the end remote of union 12 for the injection needle. In order to prevent the cylinder from bursting when sterilizing the same, the piston consists of a material of which the coefficient of thermal expansion is smaller than that of the cylinder material. The piston, for example, may be made of quartz glass, quartz material, a heat-resistant ceramic material or of Invar steel, whilst the cylinder may be made of heat-resistant glass or clear quartz glass. Preferably, the piston is made of quartz material, and the cylinder of clear quartz glass, which is best suited therefor on account of its small coefficient of expansion.

As shown in Fig. 1, piston 11 is mounted over a finger-like peg 13 which comprises a germicidal source of energy such as a source of heat or of ultraviolet radiation, and is secured to a cap 14. In the latter is provided an electric plug connection 15. A cover 16 is mounted over the syringe and is detachably secured to cap 14 by means of a bayonet catch 17. Cover 16, in a form of invention not shown, may be so tall that an injection needle secured to union 12 is accommodated inside the cover. 30 The material of the cover is so chosen that the latter retains as much as possible the heat or radiation emitted from peg 13. In the cover is disposed a heating coil 18 surrounding cylinder 10 and being connected to plug connection 15. The heating coil, however, may be omitted.

Sterilization of syringe 10, 11 is carried out as follows. If peg 13 comprises a source of heat, piston 11 and cylinder 10 are heated thereby until the germs and spores are charred or incinerated. Such germicidal action may additionally be boosted yet from the outside by means of heating coil 18. In order to speedily cool off the syringe, the entire assembly including cover 16 may afterwards be immersed in cold water.

45 If peg 13 comprises a source of ultraviolet radiation, the germs and spores on piston 11 and cylinder 10 are killed off through such radiation. In this case, at least the piston 11 has to be made of a material which is pervious for such radiation, for example of quartz material or quartz glass. The sterilizing action at the same time may be boosted from the outside through heating coil 18.

55 Instead of providing a particular peg 13 over which the piston 11 is mounted, a source of heat may be rigidly built in the hollow space of piston 11 directly, as shown in Fig. 2. To such end, an insulating tube 19 is provided in the piston, on which is coiled a heating wire 20. To the rear end of piston 11 is secured a cap 21 made of insulating material and comprising a pair of connecting contact elements 22, which are connected to the heating wire 20. Cap 21 also serves as handle for actuating the syringe.

60 To sterilize the syringe, cap 21, similarly as the cap of a radio tube or incandescent lamp, is mounted in a holder to render possible the supply of current to heating coil 20. As in the first form of invention described, sterilization here also is carried out in the assembled state of the syringe.

65 As shown in Fig. 3, a source of ultraviolet radiation is fixed directly in the hollow space of piston 11. To such end, the latter itself is formed as low-pressure mercury-vapor discharge tube and comprises a rodlike elec-

trode 23 and a gridlike electrode 24 which surrounds electrode 23. To connect the electrodes, again contact elements 22 are provided in an insulating cap 21 as in the last example described. Since a low-pressure discharge tube causes no substantial heating, the syringe after sterilization is quickly ready for application.

In conventional all-glass syringes, the piston has the same diameter over its entire length and conforms to the inner wall of the cylinder, as shown in Fig. 1. When replenishing the syringe, the aspirated injection liquid wets the piston over its entire length owing to capillary action. When withdrawing the piston, germs from the air may settle thereon, which in the case of somewhat extended injections, which for example may last ten minutes, might rediffuse into the injection liquid. In order to eliminate such risk also, the piston, as shown in Fig. 4, is provided with a peripheral neck 25 in which may collect the liquid flowing through capillary action along the piston head. That portion of the piston which is situated rearwardly of neck 25, then is not wetted by the injection liquid.

For the same purpose, a piston shank 27 of reduced diameter and cross-section relative to the piston head is formed by a shoulder 26 on piston 11, as shown in Figs. 2, 3 and 5. In this case, a safeguard may be provided against unintentional movement of piston 11 out of the cylinder 10, as shown in Fig. 5. To such end, pegs 28 are rigidly riveted to a spring clip 29 and project through holes in the wall of the cylinder rear-end portion. Said clip surrounds cylinder 10 and pushes the pegs 28 against piston shank 27. The pegs 28 thus form stops coaxing with a piston shoulder 26 and may escape outwardly when the piston is entirely withdrawn from cylinder 10 by overcoming a certain resistance.

The injection syringes described and shown afford the following advantages over syringes known so far:

Sterilization from the inside affords a more intensive and quicker utilization of the germicidal action of heat or ultraviolet radiation. Thus the time of sterilization or the energy of the germicidal source of energy may be decreased.

The risk of introducing germs from the air into the syringe is practically entirely eliminated by reason of the fact that the syring can be sterilized in the assembled

state and the piston is provided with a neck or a shouldered shank.

What we claim as new and desire to secure by Letters Patent, is:

5. In an injection syringe having a cylinder, a hollow piston displaceable within said cylinder, and means for radiating energy disposed within the hollow of said piston, said piston being composed at least in part of material transparent to the energy radiated by said radiating means, whereby said cylinder together with a liquid when contained therein may be disinfected in assembled state without removal of said piston.

2. In a syringe according to claim 1, said piston comprising a tubular member having a closed head normally seated in said cylinder and having an open end opposite said head.

3. In a syringe according to claim 1, said cylinder being composed of a material resistant to the energy radiated by said radiating means, the thermal coefficient of the material of which said cylinder is composed being greater than the thermal coefficient of the material of which said piston is composed.

25. In a syringe according to claim 1, said piston having a head portion conforming to the inner wall of said cylinder and a shank portion of reduced cross-section relative to said head portion, whereby said shank portion is maintained out of contact with said inner cylinder wall.

30. In a syringe according to claim 1, the hollow of said piston being sealed off and being filled with a gas, said radiating means including electrodes for activating said gas to radiate energy, whereby disinfecting is effected by electric gas discharge initiated within said piston.
